Primary Examiner — S. Bryan Reinholdt, Jr.

(57) **CLAIM**

The ornamental design for a container lid, as shown and described.

DESCRIPTION

FIG. 1 is a rear, top perspective view of a container lid, showing my new design;

FIG. 2 is a front, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view of the container lid, shown in an alternate position.

The broken lines in the figures illustrate portions of the container lid that form no part of the claimed design. The additional broken lines in FIG. 9 depict environment that form no part of the claimed design.

1 Claim, 9 Drawing Sheets
